United States Patent Office.

JAMES H. DURHAM AND SANFORD RISING, OF LAFAYETTE, INDIANA.

Letters Patent No. 65,890, dated June 18, 1867; and dated December 18, 1866.

IMPROVED SASH-SUPPORTER.

The Schedule referred to in these Letters Patent and making part of the same.

TO ALL WHOM IT MAY CONCERN:

Be it known that we, JAMES H. DURHAM and SANFORD RISING, of the city of Lafayette, in the county of Tippecanoe, and State of Indiana, have invented a new and useful lock, which may be applied to window-sashes or shutters, or other sliding apparatus, to be known as the Reversible Eccentric Lock; and we do hereby declare that the following is a full, clear, and exact description of the construction and operation of the same, reference being had to the annexed drawings, making a part of this specification, in which—

Figure 1 is a perspective view as applied to a vertical sliding apparatus.

Figure 2 shows the internal arrangements of the lock with its different positions while in operation.

Figure 3 shows a longitudinal elevation.

Figure 4 gives two views of the key on which the lock revolves when operated.

Figure 5 shows the shape and construction of the spring which, in combination with the key, causes the lock to operate in the manner hereafter described.

A, fig. 1, is a circular lock constructed of two metallic disks, between which is firmly secured a circular piece of India rubber or other suitable elastic material, from which has been cut a portion, forming the peculiar recess, as shown at D, fig. 2, and into which is inserted the spring E, figs. 2 and 5. B, figs. 1 and 3, is a screw securing or holding the parts together, and also serving as a knob or handle. C, figs. 1, 2, 3, and 4, is a stationary or fixed key placed near the periphery or circumference of the metallic disks, in order that the lock should be eccentric or cam-like in its operation as it revolves around said key, which is also the hinge or point on which the lock turns. The ward of the key is shown at C', fig. 4, and extends between the arms of the spring E, as shown in fig. 2. F, figs. 2 and 5, is a steel or brass spring constructed in the form or shape shown at fig. 5, and inserted in the recess in the rubber, as shown at fig. 2, letter D. The spring is made to fit closely to the recess at the points d, d, fig. 2, in order that the rubber may act as a support to the spring, and also impart its own elasticity to aid the spring in its action. The whole machine is secured to the window or other apparatus by the screw G, figs. 1 and 3, which passes through the key C, figs. 1 and 3, and holds it firmly in position, and thus secures the whole machine to its proper place. The dotted lines H H', fig. 2, show the different positions in which the lock is placed when in use, for instance, on a window. H shows the window fastened down, while the lock reversed as at H' holds it up, and fig. 2 proper shows the position in which the lock is held while being secured to the sash. The machine may be fastened to either side of the sash or window-frame, and operate as described, or on other sliding apparatus in like manner. Therefore—

What we claim as our invention, and desire to secure by Letters Patent, is—

The rubber cam, having a V-shaped recess wherein is placed the spring E, as constructed, with screw-pivot G passing through the collar C, with a wing, e, for spreading the spring when arranged between the plates A, in the manner and for the purposes set forth.

JAMES H. DURHAM,
SANFORD RISING.
